PHONOGRAPH

Charles Huenlich, Bloomfield, and Heinrich F. Max Gramann, Orange, N. J., assignors to Thomas A. Edison, Incorporated, West Orange, N. J., a corporation of New Jersey

Application March 12, 1938, Serial No. 195,492

11 Claims.

(Cl. 274—17)

Our invention relates to phonographs and more particularly to the sound-translating devices employed in commercial phonographs of the dictating machine type. It is especially concerned with sound-translating devices which are adapted for both sound recording and sound reproducing.

The form of sound-translating device which is adapted for both sound recording and sound reproducing may principally employ suitable vibratile means, a recorder stylus and a reproducer stylus operatively related to the vibratile means, means for moving the respective styli into and out of operative position with respect to a record, and a suitably mounted means for biasing the reproducer stylus against the record when the translating device is adjusted for reproducing. When the translating device is adjusted for sound recording, the biasing means usually effects no useful purpose. In practice, the biasing means is then permitted to engage the record, and be supported thereby, at a position in advance of the recorder stylus during the recording operation. The consequent riding or dragging of the biasing means on the record has tended to catch record chips, which are cut away by the recorder stylus, and smear them along the record surface. This smearing action does therefore mar or roughen the record surface and cause an increase in the surface noise.

It is an object of our invention to avoid such smearing action by maintaining the biasing means free of the record during the operation of recording thereon.

It is another object to provide means for suitably maintaining the reproducer stylus biasing means free of, and in a predetermined position with respect to, the record during the operation of recording thereon.

It is another object to provide means, conditioned for operation by the adjustment of the sound-translating device to recording position, for moving the reproducer stylus biasing means into a position wherein it is free of the record.

It is another object to provide means, in a combined sound-recording and sound-reproducing device, for moving the reproducer stylus biasing means into a record engaging position and then a predetermined distance from such position as the device is adjusted for recording purposes.

It is another object to provide, in phonographs, means which are responsive to the control means of the phonograph for moving the reproducer stylus biasing means into a predetermined posi-

tion with respect to a record, and for supporting the biasing means in such position free of the record during the operation of recording.

It is another object to provide means in phonographs, for supporting the reproducer stylus biasing means free of the record, which is conditioned for operation incidental to the operation of adjusting the phonograph for recording and which is operated as an incident of the operation of the machine.

Other and allied objects will more fully appear from the following description and the appended claims.

In the description of our invention, reference is had to the accompanying drawings, of which:

Fig. 1 is an elevational view, partly in cross section, of such portion of a phonograph as is sufficient to show the application of a preferred embodiment of our invention thereto;

Fig. 2 is a bottom plan view of a portion of the mechanism shown in Fig. 1;

Fig. 3 is an elevational view, partly in cross-section, showing the mechanism of Fig. 1 in an operated position;

Fig. 4 is a detailed top plan view showing the arrangement of a portion of the mechanism shown in Fig. 1;

Fig. 5 is a cross-sectional view, taken on the line 5—5 of Fig. 4, showing principally the various parts of the reproducer stylus biasing means;

Fig. 5a is an enlarged view of a portion of Fig. 5;

Fig. 6 is a view, similar to that of Fig. 5, showing the various parts of the reproducer stylus biasing means in operated position;

Fig. 7 is a top plan view of another form of biasing means employed in a modified form of our invention;

Fig. 8 is an elevational view, partly in cross-section, of a portion of the modified form of our invention, illustrating the means for lifting the biasing means from the record;

Fig. 9 is an elevational view of a portion of a phonograph showing the modified form of our invention employing the biasing means of Figs. 7 and 8, and a mechanism for lifting the biasing means which is conditioned for operation by the adjustment of the machine for recording and operated as the machine is put in action;

Fig. 10 is a bottom plan view of a portion of the modified form of our invention as shown in Fig. 9; and

Fig. 11 is an elevational view of another modification of our invention.

Reference being had to the drawings, and par-

ticularly to Fig. 1, there will be seen a portion of a conventional phonograph comprising a carriage 1 slidably mounted on the longitudinal rods 2 and 3 for longitudinal movement with respect to a record 4. Such longitudinal movement of the carriage 1 may be effected by the rotation of a feed screw 5 which is adapted to be engaged by a feed nut 6 carried by a U-shaped bracket 6' secured to an arm 7 which is hinged to the carriage 1 about the pivot 8. The arm 7 is guided by a guide rod 9 and is normally biased leftwardly by means of a compression spring 10 disposed about the rod 9. Movement of the feed nut 6 into and out of engagement with the feed screw 5 may be effected by means of a control lever 11 pivotally mounted on and slidable along the longitudinal rod 2 and having a hub 12 bearing a V-shaped cam portion 13. This lever 11 extends through a slot 14 provided in the carriage 1 and is adapted to move the feed nut 6, as it is rocked forwardly and rearwardly about the rod 2. Such movement of the feed nut 6 is effected by means of a slidably mounted pin 15 engaging at one end with a roller 13' provided at the top of the cam portion 13, and at its other end with the arm 7. When the control lever is in a central or neutral position the pin 15 is in its most rightward position and the feed nut 6 is out of engagement with the feed screw 5; whereas when the control lever is rocked either forwardly or rearwardly the roller 13' moves off of the head of the pin 15, and therefore the feed nut 6 moves into engagement with the feed screw 5, as by the force of the spring 10.

The carriage 1 has a forwardly extending arm 1' supporting a translating device 16 which is adjustable for either recording or reproducing purposes. This device has, for its main frame, a cup-shaped member 17 which is provided with a bifurcated and downwardly extending lug 18. This lug carries at its lower end a pivot shaft 19 having conical ends extending beyond the lug. A circular casing 20 having a sound chamber is pivotally mounted substantially concentrically with the cup-shaped member 17 by means of a mounting bracket 21 secured to the circular member 20 and comprising a pair of spring arms 21' engaging the conical ends of the pivot shaft 19. In order that the displacement between the spring arms 21' may be adjusted so as to bring the arms 21' into proper relationship with the conical ends of the shaft 19, there is provided a headed screw 22 which passes freely through one of the spring arms 21' and threads into the other, as shown in Fig. 4.

The circular casing 20 has a central dome 23 (see Fig. 1) which engages the internal spherical end portion 24 of a tube 25 to form a universal joint therewith. The tube 25 extends upwardly into a neck 17' provided on the cup-shaped member 17. The upper end 25' of the tube 25 is flanged outwardly to fit closely with the neck 17' and slidably therealong. The spherical end portion 24 of the tube 25 is suitably retained to the dome 23 so that any swinging movement of the circular casing 20 will effect also a sliding movement of the tube 25 within the neck 17'. The bottom 28 of the circular casing 20 is closed by a vibratile means or a diaphragm 26 which is held in place by a suitable gasket 27 shown in Fig. 5a.

There is thus formed within the circular casing 20 a sound chamber, which communicates with the neck 17' by way of the tube 25, this neck being adapted for making suitable connection with a speaking tube (not shown). To the diaphragm 26 there is secured a stirrup 28 carry-

ing a recorder stylus 29 at its outer end, as shown in Figs. 3 and 5.

Positioned below the casing 20 is the reproducer stylus biasing means comprising a biasing weight 30 having a central aperture 30' through which the stirrup 28 may freely pass. This weight is secured to a rearwardly extending bracket 31 which is pivotally mounted on the central portion of the shaft 19 carried by the lug 18. In order that the weight 30 may swing leftwardly and rightwardly, longitudinally of the record 4, it is pivotally connected to the bracket 31 by means of the shoulder screw 32. The biasing weight 30 is adapted to provide a suitable biasing force for a reproducer stylus 33 shown in Fig. 3. For this reason there is provided an arcuately-shaped lever 34 pivotally mounted on the weight 30, by a pin 35, and extending downwardly through the aperture 30'. The forward end 34' of the lever 34 carries the reproducer stylus 33, and the rearward end 34'' of the lever extends within the stirrup 28.

It will be seen that in the adjusting of the translating device 16, the following results are effected: When the translating device is adjusted into a reproducing condition the casing 20 is maintained in an upward position wherein the recorder stylus is free of the record 4, as shown in Fig. 1. The weight 30 is, however, rendered free to move downwardly until it is supported by the record through the stylus lever 34. When the weight 30 is so supported, the rearward end 34'' of the stylus lever bears against the lower inner side 28' of the stirrup 28, and the reproducer stylus 33, carried at the forward end 34' of the stylus lever, bears against the record 4. The downward force of the biasing weight 30 thus biases the reproducer stylus 33 against the record 4; this downward force moreover maintains the rearward end 34'' of the stylus lever 34 in contact with the stirrup 28 so as to couple the reproducer stylus 33 with the diaphragm 26. When the translating device is, however, adjusted into a recording condition, both the casing 20 and the weight 30 are rendered free to move downwardly towards the record. The casing 20 will thus move downwardly until it is supported by the record 4 through the engagement of the recorder stylus 29 with the record, and the biasing weight 30 will move downwardly into a position intermediate of the casing 20 and the record 4, as is hereinafter described. The means for so adjusting the translating device 16 comprises the aforementioned control lever 11; as this lever is moved from its neutral position into its forward and rearward positions, the translating device 16 is respectively adjusted into recording and reproducing conditions by means of a mechanism hereinafter described.

In order that the carriage 1 may suitably accommodate the control lever 11, it is provided with an enlarged channelled portion 1'' which overlies and is concentric with the guide rod 2. Centrally located with respect to the channelled portion 1'' and slidably mounted on the guide rod 2 is a sleeve 36 having a flange 37' at one end which is secured, as by the screws 31, to the right-hand side of the channelled portion 1'', this portion having at its right-hand side a suitable slot 36' for receiving the sleeve 36, as shown in Fig. 2. At its left-hand side, the portion 1'' has a centrally located aperture 36'', as shown in Fig. 10, through which the sleeve 36 extends. Rotatably mounted on the sleeve 36, and within the channelled portion 1'', is another sleeve 38

to which is secured the control lever 11 having the hub 12 surrounding the sleeve. In the channelled portion 1" overlying the guide rod 2 there is provided the slot 14, extending transversely of the rod 2, through which passes the arm of the control lever 11, permitting thereby a forward and rearward rocking movement of the lever 11 with respect to its central or neutral position.

At the sides of the hub 12, and rotatably mounted on the sleeve 38 are the left and right discs 39 and 40 having the respective forwardly extending fingers 41 and 42. These fingers are adapted to engage the under sides of the forward projections 43 and 44 provided on the respective casing 20 and floating weight 30. The left disc 39 is spring biased in a clockwise direction; that is, the respective finger 41 is biased upwardly by means of a forwardly extending arm 45' contacting the underside of the finger 41, pivoted on a pin 46, and biased upwardly by a spring 47'; whereas the right-hand disc 40, having the finger 42 for controlling the movement of the biasing weight 30, is normally biased in a counter-clockwise direction, as by the downward force of the biasing weight 30, so that its finger tends to move downwardly. Such downward movement of the finger 42 is however limited and controlled, as is hereinafter described, by means of a forwardly extending arm 45 pivotally mounted on the pin 46 and biased upwardly by means of a spring 47.

When the control lever 11 is in a neutral position, as shown in Fig. 1, it is adapted to maintain both the casing 20 and the reproducer stylus biasing means in such respective upward positions as will permit them to be free of the record 4 so that the record may be freely mounted on and removed from a suitable record support (not shown).

For imparting the proper movements to the discs 39 and 40 to condition the translating device 16 for recording and reproducing, as by the respective forward and rearward rocking movements of the control lever 11 from neutral position, there are provided the radially extending projections 48 and 49 on the hub 12. The projection 48 carries a pin 48' extending from each side thereof and substantially parallel with the rod 2. As the lever arm 11 is rocked forwardly from its central or neutral position, the pin 48' is adapted to engage the top sides of the respective fingers 41 and 42 and move them downwardly with the movement of the lever. Although the right-hand finger 42 is biased downwardly it is maintained in contact with the pin 48', as the lever 11 is moved forwardly from its neutral position, by virtue of a relatively strong upward biasing force applied to the member 45 by the spring 47 which slidably engages the under side of this finger. As the lever 11 is moved rearwardly from its neutral position the leftward finger 41 will move therewith, by virtue of the upward biasing force acting thereon as caused by the spring 47', until the casing 20 engages with the under side of the inverted cup member 17. The rightward finger 42 is however adapted to move downwardly, as the lever 11 is moved rearwardly, in order that the weight 30 may be free for supplying the biasing force to the reproducer stylus 33. Such downward movement of the finger 42, is effected by means of the projection 49, provided on the hub 12, which serves as a cam for moving the member 45 downwardly, as the lever 11 is moved rearwardly, thereby permitting the finger 42 to move down-

wardly by virtue of the force of gravity acting on the weight 30.

When the translating device 16 is conditioned for recording, it is important that the weight 30, which is interposed between the casing 20 and the record 4, be maintained free of the circular casing 20. In order that such relative positioning of the weight 30 to the casing 20 is maintained during recording, it has been the practice to provide the reproducer stylus biasing means 10 with a polished spherical ball 50 (see Fig. 7) which is mounted on the under side of the weight 30, in advance of the recorder stylus 29, and adapted to slide on the record 4 and thereby support the weight 30 in a substantially fixed 15 position relative to the record 4. The weight 30 is then also maintained in a substantially fixed position relative to the casing 20 since the casing is also supported by the record, as by the engagement of the recorder stylus 29 with the record 4. 20 Such engagement of the ball 50 with the record 4 is frequently found objectionable for reasons hereinbefore mentioned.

It is a purpose of this invention to provide suitable means, automatically operated incidental to the operation of conditioning the phonograph or translating device 16 for recording, for preventing the ball 50 from bearing upon the record surface during the recording operation. These means operate to support the reproducing 30 stylus biasing means in a position free of the record and preferably at a predetermined distance from the same. For effecting such results we provide a suitable actuating member which is adapted to coact with a suitable device, 35 provided on the weight 30, and by such coaction move the weight to a proper position with respect to the record 4, as the control lever 11 is moved forwardly to condition the translating device for recording. The device provided on the weight 30 for coacting with the actuating member, and the means for properly moving the actuating member, as by the forward movement of the control lever 11, are each herein described in various forms. In each form the actuating 40 member is operated by means which are conditioned for operation by the movement of the control lever 11 through the end portion of its forward travel to recording position. Moreover, in each form these means may be operated by 45 energy which is stored incidental to the operation of moving the control lever 11 from recording position to neutral position. A preferred embodiment of these means is now described in detail.

In a preferred embodiment of our invention, shown in Figs. 1 to 6 inclusive, the reproducer stylus biasing means is provided with a member 54', movably mounted on the weight 30, which is adapted to engage the record. In operation, the weight 30 is first lowered so as to bring the member 54' into contact with the record; the weight is then maintained substantially in a fixed position while its movable member 54' is removed from contact with the record. For 55 effecting such operation of the weight there is provided an actuating member 51 which is pivoted, as by the pin 52, to a bracket 53 suitably secured to the carriage 1, this actuating member being provided with a roughened or serrated 60 face 51' which is adapted to cooperate with the weight 30 in a manner hereinafter explained.

Reference being had to Figs. 4, 5 and 6, it will be seen that the member 54' comprises a bracket 54, having a U-shape or any other suit- 70

able form, which is pivotally mounted on the weight 30, as by the pin 35 which holds the stylus arm 34. This bracket is provided with a lug portion 55 having an aperture for holding a suitable advance ball 56, and is normally resiliently held in a downward position by means of a torsion spring 57 disposed about the pin 35. Thus, by these means the weight 30 is resiliently supported at a predetermined distance from the record whenever the weight is lowered so that the ball 56 is brought into a record-contacting position.

In order that the weight 30 may be substantially maintained in such position relative to the record and have its related parts, such as the advance ball 56, fully free of the record 4, as by a suitable movement of the actuating member 51, the bracket 54 is provided with an extension 58 having a cam face 58' at its end, as shown in Fig. 5. This cam face is adapted to coact with a pin 59 carried by a slidable member 60. The member 60 is slidably supported for movement relative to the weight 30 by means of an apertured bracket 61 and an apertured flange 30" on the weight 30 through which the member 60 passes, the bracket 61 being secured to the weight 30 by a screw 61'. Forward movement of the member 60 is limited by the engagement of the pin 59 with the inner side of the flange 30". The member 60 is normally retained in its most forward position by reason of a spring 62 located on the underside of the weight 30 and retained in place by a screw 62'. When the member 60 is in such forward position, the lowered position of the downwardly urged bracket 54 is defined by the engagement of the pin 59 with the same face 58', as shown in Fig. 5.

A rearward movement of the member 60 will cause the bracket 54 to be swung upwardly, as by the sliding engagement of the pin 59 with the cam face 58' on the extension 58. In the operation of our invention such rearward movement of the member 60 is effected by means of the actuating member 51. In order that the weight 30 may be substantially held in fixed position during the rearward movement of the member 60, this member is suitably extended and provided with a knife edge 60', at its forward end, and the actuating member 51 is provided with the serrated face 51" adapted to engage the edge 60'. Such engagement is adapted to occur when the radial line from the pin 52, about which the actuating member 51 is pivoted, to the point of contact between the slidable member 60 and the actuating member 51, is substantially normal to the longitudinal axis of the member 60.

In order to insure that the biasing weight 30 will be supported in a substantially predetermined position with respect to the record 4, the weight 30 and bracket 54 are first permitted to move downwardly until the weight is supported by the record 4, as by the contact of the ball 56 with the record; the weight 30 is then maintained in such supported position, as by the engagement of the knife edge 60' with the serrated face 51", while the bracket 54 is moved upwardly with respect to the weight to free the ball 56 of the record. For this reason the finger 42, which controls the weight 30, is adapted to move downwardly, free of the weight 30, during the first portion of the forward travel of the control lever 11 from neutral position; the actuating member 51 is then operated by the forward travel of the control lever 11 through its remaining portion.

The means for effecting the proper movement of the actuating member 51, in this preferred embodiment, comprises a weight 63 which is secured to a shaft 64 by means of the screws 65. The shaft 64 is journaled at one end in the left end wall of the channelled portion 1", and at its other end in a bracket 66 secured to the wall of the carriage 1 by the screw 67. Secured to the shaft 64, adjacent to the bracket 66, is a plate 68 having a laterally extending pin 69 adapted to engage the cam face 51' provided on the rear edge of the actuating member 51. Swinging downward and upward movements of the weight 63 will therefore operate the actuating member 51 respectively forwardly and rearwardly by reason of the co-operation of the pin 69 with the cam face 51', this cooperation being suitably maintained by means of a spring 70 providing a biasing force of the actuating member 51 against the pin 69.

Substantially diametrically opposite of the pin 69 on the edge of the plate 68, there is provided a cam face 68' which coacts with a laterally extending pin 71 carried by a collar 72. The collar 72 is secured to the sleeve 38, as by the set screw 72', and thus it turns in unison with the control lever 11. When the control lever 11 is in its most forward position, the weight 63 is adapted to be in its most downward position wherein it is maintained by the engagement of the pin 71 with the cam face 68'. As the control lever 11 is moved through the first portion of its return travel from recording position to neutral position, the weight 63 is moved to its upward position, by the coaction of the cam face 68' with the pin 71, thereby effecting the storage of potential energy therein. In order that the weight 63 may be held in its upward position, as the control lever 11 is moved through the remaining portion of its return travel, there is provided a latching pawl 73 which catches a tab 74 secured to the weight 63 by the screws 75. The pawl 73, as shown in Fig. 2, is pivoted about a pin 76 which is journaled in the left end wall of the channelled portion 1". The latching pawl 73 engages the rearward edge of the tab 74 and is biased thereagainst for supporting the weight 63 in its upward position, the biasing action being effected by means of a spring 77. In order that the pawl 73 may be released from the tab 74 by the movement of the control lever 11 through the end portion of its forward travel, there is provided another pin 78, on the collar 72, which engages the pawl 73 to unlatch the same from the tab 74 as the lever 11 nears the end of its forward travel. The weight 63 will then move downwardly, as by gravity, until it is stopped by the engagement of the pin 71 with the cam face 68'. Such downward movement effects the release of the energy stored in the weight and causes a forward movement of the actuating member 51.

The operation of the preferred embodiment of our invention is thus briefly as follows: As the control lever 11 is moved through the first portion of its forward movement from neutral position, the fingers 41 and 42 are moved downwardly, thereby permitting the casing 20 and the reproducer stylus biasing means to move downwardly so as to rest upon the record 4. As the control lever 11 is moved through the remaining portion of its forward travel, the pin 78 engages the pawl 73 to move it rearwardly and thereby release the weight 63. The weight 63 then moves downwardly to effect a forward

movement of the actuating member 51, as by the engagement of the cam face 51' with the pin 69. The forward swinging movement of the actuating member 51 causes it to engage with the slide member 60 and move it rearwardly. Such rearward movement effects an upward swinging movement of the bracket 54, thereby freeing the reproducer stylus biasing means of the record 4.

As the control lever 11 is moved through the first portion of its return travel from recording position, the pin 78 on the collar 72 moves forwardly permitting the pawl to move into a locking position. Simultaneously therewith the pin 11, also on the collar 72, engages the cam face 68' to move the weight 63 upwardly. As the weight 63 moves upwardly the tab 74 slides over the pawl 73 to lock the weight in position, and the actuating member 51 moves rearwardly to cause the biasing weight 30 to rest again on the record 4. As the control lever is then moved through the remaining portion of its travel the fingers 41 and 42 are moved upwardly to return the casing 20 and biasing weight 30 to their upward positions.

Reference being had particularly to Figs. 7 and 8 there will be seen a modified form of reproducer stylus biasing means having a weight 30a which, as the translating device is adjusted into a recording position, is first moved into a position wherein it is supported by the record and thereafter moved a predetermined distance from the record. The weight 30a is provided with an advance ball 50 rigidly mounted on the under side of the weight. As the weight 30a is moved downwardly the ball 50 is adapted to engage the surface of the record 4 and thereby support the weight. In the flanged portion 30a' of the weight 30a, there is provided a bifurcated lug 80 through which passes a pin 81 serving as a pivot for a light U-shaped tilting lever 82. This tilting lever extends downwardly and is provided with a forwardly curved portion adapted to coact with the serrated face 51a' of an actuating member 51a. Normally the lever 82 is resiliently held in a counterclockwise direction by means of a spring 83. However, as the actuating member 51a is moved forwardly, its serrated face 51a' lockingly engages the tip of the lever 82 to effect a clockwise movement thereof, thereby imparting an upward tilting movement to the weight 30a from its position wherein it is supported by the record.

In this modified form of reproducer stylus biasing means the actuating member appears in slightly changed form from the aforescribed member 51 and is given the reference character 51a. For operating the actuating member 51a there may be provided means whereby energy is stored with the return of the control lever from recording position. These means are then conditioned, as by the movement of the control lever 11 through the end portion of its forward travel, so that the stored energy may be released to effect the proper movement of the actuating member 51a. In this modification of our invention the energy release is effected by the power or energy supplied by the driving means of the phonograph; wherefore this modified form of our invention is now described in detail.

Reference being had to Figs. 9 and 10 there will be seen the actuating member 51a pivoted about the pin 52 and having a serrated face 51a' adapted to coact with the tilting lever 82. The actuating member has, at its hub, a V-shaped

cam 84 adapted to cooperate with a peripheral notch 85 provided on a collar 86 secured to the sleeve 38. The collar 86 will thus turn in unison with the control lever 11. When the control lever 11 is in its neutral position the tip of the cam 84 engages the periphery of the collar 86 to maintain the actuating member 51a in a rearward position. When the control lever 11 is in its forward position, as shown in Fig. 9, the notch 85 is adjacent the tip of the cam 84 so that the actuating member 51a may then move forwardly.

At the lower end of the actuating member 51a there is pivotally connected a bifurcated member 87, as by the screw 88, in which is threaded a horizontal rod 89 extending rearwardly through an apertured front wall of a bracket 90 which is secured to a side wall of the carriage 1 by means of the screws 91. The rod 89 may be adjusted with respect to the bracket 90, as by turning the rod in the member 87, and locked in position by the locking nut 91. At the forward end portion of the rod 89 there is secured a collar 92, as by the pin 92'. Disposed about the rod 89, between the collar 92 and the front wall of bracket 90, is a compression spring 93 biasing the actuating member 51a forwardly. Thus, when the control lever 11 and the actuating member 51a are in their respective forward positions, so that the cam 84 engages the notch 85, it will be seen that a rearward movement of the control lever 11 from such forward position to neutral position, will cause the actuating member 51a to be moved rearwardly to effect a storage of energy by the compression of the spring 93. The actuating member is normally held in such rearward position by means of a latching pawl 94 which is adapted to engage a notch 94' provided in the rear end portion of the rod 89. The pawl 94 is biased in a clockwise direction by means of a spring 95 and is pivoted to the bracket 90, as by the pin 96. Thus, the actuating member 51a is not permitted to move forwardly with the forward movement of the control lever 11; the actuating member is however conditioned so that it may move forwardly, as by the force of the spring 93, upon the release of the pawl 94 from the notch 94'.

Although it is not important that the reproducer stylus biasing means be removed from contact with the record 4 when the translating device 16 is conditioned for recording and the record 4 is not being rotated, it is important that the biasing means be moved free of the record upon the initial rotation of the record subsequent to the moving of the biasing means into contact therewith. In this modified form of our invention we effect a lifting of the weight 30a simultaneously with such initial rotation of the record by the provision of means for releasing the pawl 94 from the notch 94' as soon as the feed nut 6 is brought into engagement with the feed screw 5, which in practice is coupled with the record 4 so that they rotate simultaneously. Since the feed nut 6 is brought into engagement with the feed nut 5 with the terminal movement of the control lever 11, and the biasing weight is brought into engagement with the record 4 by the forward movement of the control lever 11 immediately preceding such terminal movement, the weight 30a is lifted from the record with the initial rotation of the record following the contact of the ball 50 with the same.

For effecting the release of the pawl 94 from the notch 94' there is provided a principally upwardly extending arm 97 pivoted about a pin 97'

and having a forwardly inclined upper end portion which is adapted to engage a downwardly extending arm 98 integral with the pawl 94. The arm 97 is biased forwardly by means of a tension spring 99 connected between a pin 99' on the arm 97 and a lug portion 90' of the bracket 90 located forwardly of the arm. The forward movement of the arm 97 is however limited by a pin 100 secured to the bracket 90. When the arm 10 engages the pin 100 the pawl 94 is out of engagement with the notch 94'. In order that the proper forward movement may be imparted to the arm 97, there is provided an arm 101, which is pivoted to the arm 97, by means of the screw 102. The arm 101 is extended forwardly and is pivoted to a block 103, as by a pin 103', which is adapted to engage the feed screw 5. At the under side of the block 103 there is provided a horizontal plate 104 in the form of an extension 15 of the bottom leg 6'' of the U-shaped bracket 6' which carries the feed nut 6, as shown in Fig. 10. The arm 101 is biased downwardly by means of a light spring 106 coiled about a pin 107, provided on the arm 97, and constrained by the pin 20 108' on the arm 97 and by a pin 108 on the arm 101. The block 103 is therefore urged downwardly upon the plate 104, as by the downward biasing of the arm 101, and abuts against the feed screw 5 (whenever the feed nut 6 is in engagement with the feed screw 5), as by the forward biasing of the arm 97. When the block 103 is in such position the arm 97 is held or restrained, as against forward movement, in a position free of the arm extension 98 of the pawl 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

In order that the arm 97 may be suitably moved rearwardly free of the arm 98 of the pawl 94 as the feed nut 6 is moved out of engagement with the feed screw 5, there is provided a link member 110 which is pivotally connected at one end, by the screw 111, to a downwardly extending lug 112 of a bracket 112' secured to the bottom side 6'' of the U-shaped bracket 6' by the pins 105. At the other end of the member 110 there is provided a longitudinal slot 113 through which passes a headed pin 114 that is secured to the arm 97.

65 It is thus seen that, when the control lever 11 is in neutral position, the actuating member is locked in a rearward position by the engagement of the pawl 94 with the notch 94'. As the control lever 11 is moved forwardly the notch 85 of the collar 86 is moved adjacently of the cam 84 so that the actuating member 51a may move forwardly, as by the spring 93. At the same time the block 103 is brought into engagement with the feed screw 5. With a rotation of the feed screw 5, the block 103 is moved upwardly, thereby rendering the arm 97 free to be

10 moved forwardly, as by the spring 99, to release the pawl 94 from the notch 94'. Upon the release of the pawl 94, the actuating member 51a is moved forwardly to engage the tilting lever 82 and to thereby move the weight 30a away from the record 4. As the control lever 11 is returned to neutral position, the actuating member 51a is moved rearwardly and the spring 93 is thereby compressed, as by the sliding engagement of the notch 85 with the cam 84; the return movement of the control lever 11 also causes the feed-nut 6 to be moved out of engagement with the feed screw 5, as hereinbefore explained. By reason of the coupling between the feed nut 6 and the arm 97, as by the link 110, 15 such disengagement of the feed nut from the feed screw effects a rearward movement of the arm 97. As the arm 97 is so moved the pawl 94 engages the notch 94' to lock the actuating member 51a in its rearward position. 20

Reference being had to Fig. 11 there will be seen another modified form of mechanism for suitably operating the actuating member 51a. In this construction there is employed the actuating member 51a having the cam 84 adapted to coact with the notch 85 provided in the collar 86. There is also pivotally connected to the lower end of the actuating member 51a, as by the screws 88, a horizontal and rearwardly extending arm 89a which is slidably supported at its rearward end portion by means of a bracket 115, secured to the carriage 1 by the screw 115'. The rod 89a is provided with an intermediately located collar 116 secured thereto by the pin 117. Between the collar 116 and the bracket 115, and disposed about the rod 89a, is a compression spring 118 biasing the actuating member 51a forwardly. The collar 116 has an upward extension to which there is pivotally connected an arm 119, as by a pin 120, having a plunger 121 at its rearward end. The plunger 121 is adapted to coact with a cylinder 122, which is pivoted to the carriage 1 by the pin 123, for forming a suitable dash-pot 124.

The operation of this modified construction is thus as follows: As the control lever 11 is moved forwardly to recording position the notch 85 is moved adjacently of the cam 84, thereby permitting the actuating member 51a to move forwardly, as by means of the spring 118. Such movement will however be delayed, as by the action of the dash pot 124. The biasing weight 30a is thus permitted to reach a position wherein it is supported by the record before the actuating member 51a moves forwardly to raise the weight from the record. As the control lever 11 is returned to neutral position the actuating member 51a is moved rearwardly by the engagement of the notch 85 with the cam 84. Such rearward movement effects a storage of energy, as by the compression of the spring 118, for suitably moving the actuating member 51a forwardly.

Although we have described and illustrated our invention in several forms, it will be obvious that many other forms and modifications of the same may be employed without departing from the scope of our invention which we now undertake to express according to the following claims.

We claim:

1. In a phonograph operable to record on and reproduce from a record and having a translating device including a frame, recorder and reproduce styli respectively movable into record-contacting positions to condition said device for recording and reproducing, and a biasing means 70

for said reproducer stylus movably mounted on said frame and urged towards the record and released for movement into contact with the record when said device is conditioned for recording: the combination of a control means movable into recording and reproducing positions to respectively effect recording and reproducing conditions of said translating device; and means operable to cause said biasing means to be supported free of the record during the operation of recording comprising a supporting member on said frame movable transversely of the direction of movement of said biasing means into engagement with the same, and means operated by said control means for controlling the movement of said supporting member.

2. In a phonograph having a support for a record and a translating device including a frame, recorder and reproducer styli respectively movable into contact with the record to condition said device for recording and reproducing, and a biasing means for said reproducer stylus movably mounted on said frame and urged towards the record and released for movement into contact with the record when said device is conditioned for recording: the combination of a control means movable into recording and reproducing positions to respectively effect recording and reproducing conditions of said translating device; a lever on said biasing means; an actuating member on said frame movable to engage said lever to move said biasing means out of contact with the record; and means, controlled by said control means, for controlling the engagement of said actuating member with said lever.

3. In a phonograph operable to record on and reproduce from a record and having a translating device including a frame, recorder and reproducer styli respectively movable into record-contacting positions to condition said device for recording and reproducing, and a biasing means for said reproducer stylus movably mounted on said frame and urged towards the record and released for movement into contact with the record when said device is conditioned for recording: the combination of a control means movable into recording and reproducing positions to respectively effect recording and reproducing conditions of said translating device; a member movably mounted on said biasing means; an actuating member on said frame adapted to coact with said member to render said biasing means, when the same is released, free of the record; and means, controlled by said control means, for controlling said actuating member.

4. In a phonograph operable to record on and reproduce from a record and having a translating device including a frame, recorder and reproducer styli respectively movable into record-contacting positions to condition said device for recording and reproducing, and a biasing means for said reproducer stylus movably mounted on said frame and urged towards the record and released for movement into contact with the record when said device is conditioned for recording: the combination of a control means movable into recording and reproducing positions to respectively effect recording and reproducing conditions of said translating device; a member movably mounted on said biasing means; an actuating member on said frame biased into coacting relationship with said member to render

said biasing means, when the same is released, free of the record; and means, controlled by said control means, for maintaining said actuating member out of said coacting relationship when said control means is in reproducing position.

5. In a phonograph operable to record on and reproduce from a record and having a translating device including a frame, recorder and reproducer styli respectively movable into record-contacting positions to condition said device for recording and reproducing, and a biasing means for said reproducer stylus movably mounted on said frame and urged towards the record and released for movement into contact with the record when said device is conditioned for recording: the combination of a control means movable into recording and reproducing positions to respectively effect recording and reproducing conditions of said translating device; a lever on said biasing means; an actuating member on said frame movable to engage said lever to move said biasing means out of contact with the record; and means, controlled by said control means, for controlling the engagement of said actuating member with said lever.

6. In a phonograph having a support for a record and a translating device including a frame, recorder and reproducer styli respectively movable into record-contacting positions to condition said translating device for recording and reproducing, and means movably mounted on said frame and urged towards the record to bias said reproducer stylus into record-contacting position, said biasing means being rendered free to move towards the record when said translating device is conditioned for recording: the combination of a control means movable into recording and reproducing positions to respectively effect recording and reproducing conditions of said translating device; a member on said biasing means adapted to contact the record to limit the movement of the biasing means towards the record when the biasing means is in released condition; a slide on said biasing means; an actuating member on said frame, responsive to the movement of said control means into recording position, for engaging said slide to operate the same and to hold said biasing means in place; and means, operated by said slide, for moving said record-contacting member away from the record.

7. In a phonograph operable to record on and reproduce from a record and having a translating device including a frame, recorder and reproducer styli respectively movable into record-contacting positions to condition said device for recording and reproducing, and a biasing means for said reproducer stylus movably mounted on said frame and urged towards the record and released for movement into contact with the record when said device is conditioned for recording: the combination of a control means movable into recording and reproducing positions to respectively effect recording and reproducing conditions of said translating device; an actuating member on said frame adapted to coact with said biasing means to maintain the biasing means free of the record when the biasing means is in released condition; driving means operable to feed said translating device along the record; and means, jointly controlled by said control means and said driving means, for controlling the coaction of said actuating member with said biasing means.

8. In a phonograph operable to record on and

- reproduce from a record and having a translating device including a frame, recorder and reproducer styli respectively movable into record-contacting positions to condition said device for recording and reproducing, and a biasing means for said reproducer stylus movably mounted on said frame and urged towards the record and released for movement into contact with the record when said device is conditioned for recording: the combination of a control means movable into recording and reproducing positions to respectively effect recording and reproducing conditions of said translating device; an actuating member on said frame adapted to coact with said biasing means to maintain the biasing means free of the record when the biasing means is in released condition; driving means operable to feed said translating device along the record; and means responsive to said driving means when said control means is in recording position for placing said actuating member in coacting relationship with said biasing means, whereby to maintain said biasing means free of the record during the operation of recording.
9. In a phonograph operable to record on and reproduce from a record and having a translating device including a frame, recorder and reproducer styli respectively movable into record-contacting positions to condition said device for recording and reproducing, and a biasing means for said reproducer stylus movably mounted on said frame and urged towards the record and released for movement into contact with the record when said device is conditioned for recording: the combination of a control means movable into recording and reproducing positions to respectively effect recording and reproducing conditions of said translating device; an actuating member on said frame movable to coact with said biasing means to move the latter out of contact with the record; means, responsive to the movement of said control means into recording position, for moving said actuating member into coaction with said biasing means; and movement-resisting means, associated with said actuating member, for delaying the coaction of said actuating member with said biasing means until the biasing means has first contacted the record.
10. In a phonograph adapted for recording on and reproducing from a record and having a translating device including a frame, recorder
- and reproducer styli respectively movable into record-contacting positions to condition said device for recording and reproducing, and a biasing means for said reproducer stylus movably mounted on said frame and urged towards the record: the combination of control means movable into recording and reproducing positions to respectively effect recording and reproducing conditions of said translating device; means operated incidental to the movement of said control means into recording position to render said biasing means free to move into contact with the record; an actuating member on said frame operable to engage said biasing means to move the same out of contact with, and through a predetermined distance from, the record; and means for controlling the operation of said actuating member comprising means for holding said actuating member out of engagement with said biasing means, rendered inoperative by the movement of said control means into recording position, and means associated with said actuating member and adapted to cause the operation of the latter to be delayed until said biasing means has first contacted the record.
11. In a phonograph adapted for recording on and reproducing from a record: the combination of a recorder stylus and a reproducer stylus; control means having recording and reproducing positions for placing said recorder and reproducer styli respectively into record-engaging positions and including a biasing means urged towards the record, said biasing means being spaced from the record and rendered effective to bias said reproducer stylus into record-engaging position when said control means is in reproducing position, and being released for movement into contact with the record as said control means is moved into recording position; means, comprising a lever pivoted on said biasing means and an actuating member having an irregular face adapted to engage an end portion of said lever, for moving said biasing means out of contact with the record; and means, automatically operated incidental to the movement of said control means into recording position, for placing said last-mentioned means in operation.

CHARLES HUENLICH.

HEINRICH F. MAX GRAMANN. 50
